UNITED STATES PATENT OFFICE

161,829

PUZZLE CHARM

Joseph Goodman, New York, N. Y.

Application November 19, 1949, Serial No. 6,139

Term of patent 3½ years

(Cl. D45—17)

To all whom it may concern:

Be it known that I, Joseph Goodman, a citizen of the United States and a resident of county of Bronx, city and State of New York, have invented a new, original, and ornamental Design for a Puzzle Charm, of which the following is a specification, reference being had to the accompanying drawing, forming a part thereof.

On the drawing:

Figure 1 is a top view of a puzzle charm showing my new design;

Figure 2 is a side view;

Figure 3 is a front view;

Figure 4 is a view of the opposite side to that shown in Figure 2;

Figure 5 is a rear view;

Figure 6 is a bottom view.

I claim:

The ornamental design for a puzzle charm, as shown.

JOSEPH GOODMAN.
